WELL TESTER

Allen H. Fletcher, Bakersfield, Calif., assignor of
 three-ninths to George D. Slusher, two-ninths
 to Burton W. McCune, and two-ninths to Ber-
 nard P. Meyer, all of Bakersfield, Calif.

Application July 14, 1934, Serial No. 735,252

13 Claims. (Cl. 166—1)

This invention relates to a testing device and relates more particularly to a well tester. A general object of the present invention is to provide a practical, effective and improved well tester.

5 During the drilling of oil and gas wells it is customary to case or line the wells with tubular casings. The lower ends of the well casings are cemented in place to seal the wells and casings against the entrance of water. Water tests 10 are made to determine if the water has been completely sealed off by the cementing in of the lower ends of the casings.

An object of this invention is to provide a reliable well tester that is operable to make satisfactory water tests and with suitable modifications is operable to test the earth formation in a gas or oil well to determine its productivity or other characteristics.

Another object of the invention is to provide a 20 well tester including a packer for sealing with the interior of a well casing or with the wall of a well, means for removing fluid from below the packer and means for equalizing the pressures at the opposite sides of the packer to allow the easy 25 release of the packer when the device is to be removed from the well. In making a well test the removal of the fluid from below the packer may result in the production of a reduced pressure and the hydrostatic pressures acting downwardly 30 on the packer may make it extremely difficult to release the packer when it is desired to remove the device from the well at the completion of the test. In the well tester provided by the present invention means is provided for admitting the 35 well pressures or hydrostatic pressures below the packer upon the completion of the test, whereby the packer may be released without difficulty.

Another object of the invention is to provide a well tester of the character mentioned that includes a pump unit for withdrawing fluid from below the packer and means adapted to be actuated by the reciprocating element of the pump to equalize the pressures at the opposite sides of the packer to provide for the easy release of the 45 packer.

Another object of the invention is to provide a well tester of the character mentioned that includes means adapted to be actuated by rotation of the test string to equalize the pressures on the packer and thus provide for its ready release. Upon the completion of a well test a substantially 50 reduced pressure may exist below the packer making it dangerous or at least undesirable to equalize the pressures on the packer by exerting an upward strain on the string to move the reciprocating el-

ement of the pump for the purpose of actuating the means mentioned above, in which case the test string may be turned to uncover relief ports and unseat valves to admit the well pressures below the packer.

Another object of the invention is to provide a well tester of the character mentioned in which the means for equalizing the pressures on the packer do not materially complicate the device and do not interfere with its proper normal operation. A further object of the invention is to provide a well tester of the character mentioned that is not liable to become "sandied" or made inoperative by accumulations of sand or other solid matter.

The various objects and features of the invention will be fully understood from the following detailed description of typical forms and applications of the invention, throughout which description reference is made to the accompanying drawings, in which:

Fig. 1 is a side elevation of one form of the invention showing it in position in a well casing during the making of a water test. Fig. 2 is an enlarged longitudinal detailed sectional view of the lower portion of the tester illustrated in Fig. 1. Fig. 3 is an enlarged longitudinal detailed sectional view of the upper portion of the tester. Fig. 4 is an enlarged transverse detailed sectional view taken as indicated by line 4—4 on Fig. 3. Fig. 5 is an enlarged longitudinal detailed sectional view of the tester illustrating the positions of the parts after the string has been rotated to equalize the pressures on the packer. Fig. 6 is an enlarged longitudinal detailed sectional view of the principal parts of the packer after the plunger has been moved past the upper limit of its normal stroke to balance the pressures on the packer and Fig. 7 is a side elevation of another form of the invention being employed to make a test of the formation in a well.

Figs. 1 to 6, inclusive, of the drawings, illustrate a form of the invention suited for making water tests at the lower end of a well casing C whose lower end portion has been cemented in the well while Fig. 7 illustrates the invention embodied in a form for making tests of the earth formation in a well to determine its productivity. The embodiment of the invention illustrated in Figs. 1 to 6 of the drawings includes, generally, a tubular body 10, a packer 11 carried by the body for sealing with the casing C to pack off the lower portion of the casing, and the opening O drilled in the body of cement B embedding the

lower portion of the casing, a pump 12 for removing or pumping fluid from below the packer 11, means 13 actuated by longitudinal movement of the test string S for equalizing the pressures 5 on the opposite sides of the packer 11 and means X adapted to be actuated by rotation of the test string S for equalizing pressures on the opposite sides of the packer.

The body 10 carries the packer 11 and forms 10 a tube or conduit for passing fluid through the packer. In the form of the invention illustrated in the drawings the body 10 comprises two threaded sections 14 and 15. A perforated tube or strainer 16 extends downwardly 15 from the lower end of the body section 14. The strainer 16 is provided with a plurality of spaced slots to admit fluid from the opening O into the body 10. The strainer 16 operates to prevent the passage of appreciable amounts of sand, etc. into 20 the body. A sub or connecting member 17 is provided on the upper end of the body section 15 and has an enlarged socket 18 in its upper end.

In accordance with the broader aspects of the invention any suitable or desirable form of packer 25 may be embodied in the tester. It is preferred to employ a packer that may be readily actuated and released by manipulation of the test string S. The particular packer 11 illustrated in the drawings includes an annular body of packing 30 19 surrounding the body section 15. A collar or sleeve 20 is provided at the upper end of the packing 19 and bears upwardly against a shoulder 21 on the body 10. A longitudinally shiftable member 22 engages the lower end of the 35 packing 19 and is provided with a downwardly and inwardly inclined outer surface 23.

The means for actuating the packing 19 includes a tail piece comprising spaced sleeves 24 surrounding the body 10 and outwardly bowed 40 springs 25 extending between and connecting the sleeves 24. The springs 25 are bowed outwardly to have movement resisting frictional engagement with the interior of the well casing C. Arms 26 extend upwardly from the upper sleeve 24 and 45 carry casing gripping slips 27. The slips 27 have downwardly and inwardly inclined inner surfaces for slidably cooperating with the surface 23 of the member 22. Downward movement of the body 10 results in downward movement of the 50 member 22 with respect to the slips 27 so that the slips are actuated outwardly into gripping engagement with the casing C and the assembly of the member 22 and slips 27 forms a relatively 55 stationary abutment against which the packing 19 is compressed and expanded into sealing engagement with the well casing.

Means is provided to releasably hold the packer 11 inoperative when the tester is being run into and out of the well. Spaced hooks 28 are provided on one of the sleeves 24 to cooperate with pins 29 on the body 10. This cooperation of the hooks 28 with the pins 29 prevents relative longitudinal movement between the tail piece sleeves 24 and the body 10 so that the slips 27 are held 60 against actuation. The pins 29 are disengaged from the hooks 28 by turning of the body 10, whereupon the body may be lowered to actuate the packer. When the packer 11 is actuated the packing 19 effectively seals off the lower portion 65 of the well and the cooperation of the packing 19 and the slips 27 with the casing C holds the body 10 against movement during the actuation of the pump 12.

The pump 12 is operable to draw or transfer 70 fluid from below the packer 11 into the test string

S. In the preferred construction the pump 12 is adapted to be connected with the lower end of the test string S and operates to carry the body 10. The pump 12 includes two relatively reciprocal elements, one a barrel 30, the other a 5 plunger 31. In the particular arrangement illustrated in the drawings the barrel 30 is the relatively stationary element of the pump and the plunger 31 is the movable element, being connected with the test string S to be reciprocated thereby. The lower end of the pump barrel 30 is connected with the body 10. A connecting member or coupling 32 may be threaded on the lower end of the barrel 30 and an opposing coupling 33 may be threaded into the socket 18 in 15 the sub 17. A nipple 34 is threaded into the coupling 32 and into the member 33 to connect the barrel 30 with the body 10. The function and operation of the threaded nipple 34 will be more fully described. The plunger 31 extends 20 downwardly into the upper end of the barrel 30 being packed or sealed about by a packing gland 35 on the upper end of the barrel. A coupling 36 connects the plunger 31 with the lower end of the test string S. The plunger 31 is in the 25 nature of a displacement plunger and has a central longitudinal opening 37 extending through it from one end to the other.

A valve is provided at the lower end of the barrel 30 to admit fluid to the barrel during the 30 upstroke of the plunger 31 and to prevent the return flow of the fluid during the down stroke of the plunger so that the plunger displaces the fluid upwardly into the test string S. The valve comprises a seat 38 and a valve proper 39 for 35 cooperating with the seat. In the particular construction illustrated in the drawings the seat 38 is threaded into the nipple 34 and carries an upwardly projecting cage 40. The valve 39 is arranged within the cage 40 and is adapted to 40 seat downwardly on a face 41 of the valve seat to close the lower end of the barrel 30. A check valve is provided in the upper end of the plunger 31 to pass the upwardly flowing fluid displaced by the plunger and to prevent a return or down 45 flow. The particular check valve illustrated includes a seat 42 on the upper end of the plunger 31 and a ball 43 arranged in the coupling 36 to cooperate with the seat. In practice it may be preferred to provide a valve in the lower end of 50 the body 10 to admit fluid into the tubular body during the upstroke of the plunger 31 and to close the lower end of the body during the downstroke of the plunger, thus retaining a column 55 of fluid in the body to be drawn into the barrel 30. The valve in the lower portion of the body 10 may include a seat 44 threaded in the lower portion of the body section 14 and a valve 45 adapted to 60 seat downwardly on the face 46 of the seat to close the lower end of the body. A suitable cage 65 47 is provided on the seat 44 to enclose and retain the valve 45.

The means 13 is adapted to be actuated by manipulation or upward movement of the pump plunger 31 to admit hydrostatic pressure to the 65 space O below the packer 11 to allow the easy release of the packer at the completion of the test. The pressure equalizing means 13 includes a rod 48 extending longitudinally through the opening 37 of the plunger. The rod 48 slidably 70 passes through an opening in a web 49 in the lower end of the plunger and has a slack connection with the valve 39. The valve controlling rod 48 extends through an opening in the upper end of the cage 40 and passes into an opening 75

50 in the upper end of the valve 39. The opening 50 has an enlarged portion which receives a stop or collar 51 on the rod 48 with substantial vertical play. A stop 52 is provided on the rod 48 and normally seats on the cage 40 to support the rod 48 in a position where the collar 51 is spaced above the lower end of the opening 50 to allow the required or necessary opening and closing movement of the valve 39. The rod 48 extends upwardly to a point within the upper portion of the pump barrel 30 and is provided at its upper end with a head 53. The rod 48 is sufficiently long so that the web 49 does not engage the head 53 when the plunger is given its normal stroke during the operation of the pump 12. When the plunger 31 is moved upwardly past the upper limit of its normal stroke the web 49 engages the head 53 to lift the rod 48 and thus unseat the valve 39. The pump plunger 31 may be provided with a port 54 which is uncovered at the upper end of the barrel 30 when the plunger is moved upwardly to lift the rod 48 and unseat the valve 39. The uncovering of the port 54 to the interior of the well or casing C of course admits fluid under pressure into the plunger 31 which fluid is free to pass downwardly through the unseated valve 39.

When the well tester embodies the lower valve 45 a connection is provided between the valve 39 and the valve 45 whereby the valves are opened substantially simultaneously by upward movement of the rod 48 resulting from movement of the pump plunger 31 past the upper limit of its normal stroke. The connection between the valves 39 and 45 includes a rod 55 extending longitudinally through the tubular body. The rod 55 has a slack connection with the valve 39. The valve 39 has a downwardly projecting extension provided with a socket or opening 56. The upper end portion of the opening 56 is enlarged and the rod 55 extends into the opening and is provided at its upper end with a head 57. The head 57 is adapted to have substantial vertical play or movement in the enlarged upper portion of the opening 56 whereby the valve 39 may freely move between its open and closed positions during the operation of the pump 12. The lower end of the rod 55 has a slack connection with the valve 45. The rod 55 passes downwardly through an opening in the cage 47 and is provided at its lower end with a head 58. The valve 45 has a socket or opening 59 which receives the head 58. The head 58 has sufficient vertical play in the opening 59 to permit the opening and closing of the valve 45. A stop 60 is provided on the rod 55 to normally seat on the cage 47 and support the rod in a position where the valves 39 and 45 are free to open and close during the operation of the pump 12.

60 After the pump 12 has been actuated to withdraw the fluid from below the packer 11 and it is desired to remove the tester from the well the test string S may be raised to move the plunger 31 to a position where its port 54 is brought into communication with the well or interior of the casing C above the upper end of the barrel 30. During this upward movement of the plunger the web 49 engages the head 53 to lift the rod 48 to first take up the slack in the connection between the rod 48 and the valve 39 and then raise the valve from the face 41. As the rod 48 continues to move upwardly with the plunger 31 the valve 39 engages the head 57 and lifts the rod 55 to open the valve 45. The fluid in the well above the packer is admitted to the interior of the

plunger 31 by the port 54 and passes downwardly through the opened valves to discharge from the strainer 16 and thus substantially equalize the pressures on the packer 11 whereby the packer may be readily released by further upward movement of the test string S.

While in most cases the pressures on the packer 11 may be readily equalized by the means 13 as just described, an extremely low pressure may be created below the packer by the operation of the pump 12 making it impracticable or hazardous to attempt to raise the test string S to actuate the means 13. Accordingly it may be desirable to embody the means X in the tester whereby the pressures on the packer 11 may be equalized without raising the test string S. The means X is operable by turning of the test string S to admit hydrostatic pressures from above the packer 11 to the opening O below the packer to provide for the easy release of the packer.

20 The means X includes a threaded connection between the nipple 34 and the body coupling member 33 that is operable to move or thread the nipple upwardly relative to the body when the test string S is rotated. This threaded connection preferably comprises comparatively heavy threads 62 on the nipple and the interior of the connection member 33. The threaded connections in the test string S usually involve right hand threads and it is preferred to employ left 30 hand threads 62 whereby the nipple 34 may be threaded upwardly by right hand rotation of the test string without endangering the threaded connections in the string. The means X includes one or more ports 63 in the wall of the nipple 34. The 35 ports 63 are positioned so that they are moved above the upper end of the coupling member 33 to be in communication with the interior of the casing C above the packer 11 when the nipple is threaded upwardly a suitable distance. A 40 flange 64^a on the lower end of the nipple 34 operates to limit the upward threading or movement of the nipple.

45 Means is provided whereby the plunger 31 may be connected with the barrel 30 to transmit 45 rotation from the test string S to the nipple 34. Splines or keys 64 are provided on the lower end portion of the plunger 31 and the lower wall of the barrel opening to cooperate when the plunger is moved to its lowermost position. The test 50 string S may be lowered to bring the keys 64 into cooperation whereupon the test string S may be turned in a right hand direction to thread the nipple 34 upwardly in the member 33 and uncover the ports 63 to pass fluid from the casing 55 C downwardly into the body 10. The rod 55 and the slack connections between the rod and the valves 39 and 45 form parts or elements of the means X. The valve seat 38 is carried by the nipple 34 so that upward movement of the nipple 60 results in corresponding upward movement of the valve seat 38 and valve 39. This upward movement of the valve 39 first takes up the slackness in the connections between the rod 55 and the valves 39 and 45 and then causes upward movement or opening of the valve 45. With the ports 63 open to the well above the packer 12 and the valve 45 open, the pressures above the packer and below the packer are substantially equalized.

65 Means may be provided to connect the plunger 70 31 with the barrel 30 when the plunger is in its uppermost position whereby the pressures on the packer 11 may be equalized by rotating the string S after the plunger has been moved to its uppermost position. Keyways 76 may be provided in 75

the body 35^a of the packing gland 35 to receive the splines 64 of the plunger 31 when the plunger is raised to the upper end of its stroke. With the plunger splines 64 engaged in the keyways 70 the 5 string S may be turned in a right hand direction to thread the nipple 34 upwardly and thus uncover the ports 63 and open the valve 45. The provision and employment of the keyways 70 are optional.

10 It is believed that the operation of the form of the invention illustrated in Figs. 1 to 6, inclusive, of the drawings will be readily understood from the foregoing detailed description. The test string S carrying the tester is first run into 15 the well to a position where the strainer 16 is adjacent the lower end of the casing C or projects within the opening O formed in the body of cement B. The packer 11 may then be actuated by turning the string S to disengage the pins 29 20 from the hooks 28 and lowering the string to actuate the slips 27 and put the packing 19 under compression. The springs 25 resist downward movement of the slips 27 so that the member 22 actuates the slips outwardly upon downward 25 movement of the body and the slips grip the casing C to hold the member 22 against further downward movement so that the packing 19 is compressed against the member 22 and actuated into sealing cooperation with the interior of the 30 casing C. After the setting or actuating of the packer 11 the pump 12 may be actuated by suitable reciprocation of the test string S. The packer 11 operates to hold the body 10 against movement during the actuation of the pump. 35 During the upstroke of the pump plunger 31 fluid from the opening O is drawn through the strainer 16 into the body 10 and into the lower end of the pump barrel 30. During the downward movement of the pump plunger 31 the valves 39 and 45 40 close and the fluid in the barrel 30 is displaced by the plunger and forced upwardly into the string S. In this manner the fluid in the opening O is pumped into the string S and is trapped therein by the valve 43 to be withdrawn in the string 45 when the tester is removed from the well. In some instances sufficient fluid may be present in the opening O or may flow into the opening O in sufficient quantities to be pumped to the surface of the ground through the test string S. In most instances, however, the liquid in the opening O will have been substantially completely pumped out after a suitable period of operation of the pump 12 and will have been trapped in the test string S. If desired, the operation of the pump 50 55 12 may be suspended for a suitable period and then resumed to determine if water or other liquid has leaked into the opening O following the first operation of the pump.

After the actuation of the pump 12 in the making of the test the pressures at the opposite sides of the packer 11 may be equalized to allow for the easy release of the packer. The means 13 may be employed to balance the pressures on the packer 11 when it is believed that the plunger 31 60 65 may be raised to the upper end of its stroke without subjecting the test string S to severe strains. To actuate the means 13 the test string S is moved upwardly to move the plunger 31 beyond the upper limits of its normal stroke and thus 70 cover the port 54 to the well above the pump barrel 30. This upward movement of the plunger 31 brings the web 49 into engagement with the head 53 and results in upward movement of the rod 48 and unseating or opening of the valve 39. 75 75 In a similar manner upward movement of the

valve 39 resulting from the actuation of the rod 48 causes upward movement of the rod 55 and opening of the valve 45. The fluid under pressure in the well above the packer 11 passes through the port 54 and flows downwardly through the tester past the opened valves 39 and 45 into the opening O to equalize the pressures on the packer. When the pressures on the packer 11 are equalized the packer may be readily released or retracted by raising the test string S which permits 10 retraction of the slips 27 and relieves the pressure on the packing 19 so that the slips and packing are both freed. Following the release of the packer 11 the tester may be withdrawn from the well. 15

In the event that extremely low pressures exist in the opening O following the actuation of the pump 12 it may be advisable to employ the means X to balance the pressures on the packer 11. To actuate the means X the test string S is first lowered to a position where the keys 64 of the plunger 31 cooperate with the keys 64 in the lower end of the barrel 30 and the string S is turned in a right hand direction. This rotation is transmitted to the nipple 34 so that the nipple is threaded upwardly through the member 33. Upward threading of the nipple 34 brings the ports 63 into communication with the well and causes upward movement of the rod 55 and opening of the valve 45. Hydrostatic pressures at the opposite sides 30 of the packer 11 are thus put in substantial equilibrium. The packer 11 may then be released as described above and the tester may be removed from the well. 35

Fig. 7 illustrates the invention embodied in a well tester for testing the productivity of the earth formation in a well. In this form of the invention the packer 11^a includes a suitably downwardly and inwardly tapering body of packing 19^a which is adapted to cooperate and seal with the wall of the well bore W at the upper end of the rat-hole A. The test string S may be lowered to a position where the packing 19^a tightly closes the upper end of the rat-hole A. The body 10, the pump 12 and the pressure equalizing means 13 and X of the tester illustrated in Fig. 7 may be identical with those previously described. The gas or liquid in the rat-hole A may be withdrawn by means of the pump 12 to relieve the hydrostatic pressure in the rat-hole. Gas or liquid that may be produced by the formation at the rat-hole A may likewise be pumped into the test string S or may freely flow upwardly through the tester into the test string. Following the completion of the test of the formation the hydrostatic pressures on the packer 11^a may be equalized by raising the test string S to actuate the means 13 or, in the event that very low pressures exist in the rat-hole A, the test string S may be turned to actuate the means X and thereby equalize the pressures on the packer. 40 45 50 55 60

Having described only typical preferred forms and application of my invention, I do not wish to be limited or restricted to the specific forms and applications herein set forth, but wish to reserve to myself any changes or variations that may appear to those skilled in the art or fall within the scope of the following claims: 65

Having described my invention, I claim:

1. A well tester for use on a test string including a body, a packer on the body for sealing off the lower portion of a well, a pump connecting the body with the string and operable by the string to transfer fluid from below the packer into the string, and means made operative by 70 75 75

manipulation of the string for admitting fluid pressure from the well above the packer to the well below the packer to equalize the well pressures above and below the packer.

5. 2. A well tester for use on a test string including a body, a packer on the body for sealing off the lower portion of a well, pump means connecting the body with the string operable to transfer fluid from below the packer into the string, and means made operative by turning of the string to equalize the well pressures above and below the packer.

10. 3. A well tester for use on a test string including a body, a packer on the body for sealing off the lower portion of a well, two elements, one a barrel, the other a plunger extending into the barrel, the elements being related for relative reciprocation to transfer fluid from below the packer into the string, one element being connected with the body, the other element being movable with the string, and means made operative by movement of the last mentioned element past a limit of its normal stroke to equalize the pressures above and below the packer.

15. 4. A well tester for use on a test string including a body, a packer on the body for sealing off the lower portion of a well, two elements, one a barrel, the other a plunger extending into the barrel, the elements being related for relative reciprocation to transfer fluid from below the packer into the string, one element being adapted to move with the string, a connection between the other element and the body comprising two telescopically related parts, one part having a port normally closed by the other part and adapted to communicate with the well above the packer, and cooperating threads on said parts; operable by rotation of the string to move the parts relative to one another and thus uncover 20 the port to equalize the pressures at the opposite sides of the packer, and means for connecting the elements for the transmission of rotation from the string to said connection.

25. 5. A well tester for use on a test string including a body, a packer on the body for sealing off the lower portion of a well, two elements, one a barrel the other a plunger extending into an end of the barrel, one element being connected with the body the other being adapted to be connected with the string whereby reciprocation of the string transfers fluid from below the packer into the string, and means made operative by movement of the string beyond a limit of its normal stroke to equalize the well pressures 30 above and below the packer including a port in one of said elements opened to the well above the packer by said movement of the string.

60. 6. A well tester for use on a test string including a body, a packer on the body for sealing off the lower portion of a well, a pump connecting the body with the string operable to transfer fluid from below the packer into the string, a valve for preventing a down flow through the body, and means operable to admit fluid to the body above the packer and open said valve to equalize the pressures on the packer.

70. 7. A well tester for use on a test string including a body, a packer on the body for sealing off the lower portion of a well, two elements, one a barrel the other a plunger extending into an end of the barrel, one element being connected with the body the other with the string whereby reciprocation of the string transfers fluid from below the packer into the string, a valve for pre-

venting a downward flow through the body, one element having a port to be opened to the well bore above the packer by movement of the string beyond a limit of its normal stroke, and means for opening the valve by said movement of the string to equalize the pressures on the packer.

8. A well tester for use on a test string including a body, a packer on the body for sealing off the lower portion of a well, a pump interposed between the body and string for transferring fluid from below the packer into the string, and screw threaded means made operative by manipulation of the string to equalize the well pressures above and below the packer.

10. 9. A well tester for use on a test string including a body, a packer on the body for sealing off the lower portion of a well, two elements one a barrel, the other a plunger extending into the barrel, the elements being related for relative reciprocation to transfer fluid from below the packer into the string, one element being carried by the body, the other element being connected with the string and having a port adapted to be put in communication with the well above the packer by movement of the string beyond a limit of its normal stroke, a valve for preventing down flow through the body, and a member connected with the last named element and associated with the valve to open the valve upon said movement of the string.

15. 10. A well tester for use on a test string including a body, a packer on the body for sealing off the lower portion of a well, pump means connecting the body with the string operable to transfer fluid from below the packer to the string, means actuated by longitudinal movement of the string for equalizing pressures on the packer, and means actuated by rotation of the string for equalizing pressures on the packer.

20. 11. A well tester for use on a test string including a body, a packer on the body for sealing off the lower portion of a well, two elements, one a barrel the other a plunger extending into an end of the barrel, one element being connected with the body the other being adapted to be connected with the string whereby reciprocation of the string transfers fluid from below the packer into the string, spaced valves for preventing down flow through the body, one of the elements having a port to admit fluid from the well above the packer into the body when the string is moved beyond a limit of its normal stroke, and means actuated by said movement of the string for opening said valves.

25. 12. A well tester for use on a test string including a body, a releasable packer on the body for sealing off a lower portion of a well, pump means interposed between the string and the body operable by reciprocation of the string to transfer fluid from below the packer into the string, and means for admitting fluid pressure from the well above the packer to the well below the packer to equalize the pressures in the well at the opposite sides of the packer.

30. 13. A well tester for use on a test string including a body, a releasable packer on the body for sealing off a lower portion of a well, pump means interposed between the string and the body operable by the string to transfer fluid from below the packer into the string, and means actuated by the string through the medium of the pump means for equalizing the pressures in the well above and below the packer.

ALLEN H. FLETCHER.
